UNITED STATES PATENT OFFICE.

WILLIAM THOMAS HESKETH, OF HAYFIELD, ENGLAND.

MACHINE FOR PRINTING CLOTH, WALL-PAPER, AND OTHER MATERIALS.

No. 852,719.

Specification of Letters Patent.

Patented May 7, 1907.

Application filed December 1, 1906. Serial No. 345,917.

To all whom it may concern:

Be it known that I, WILLIAM THOMAS HESKETH, a subject of Great Britain, residing at Stones House, Hayfield, in the county of Derby, England, have invented new and useful Improvements in Machines for Printing Cloth, Wall-Paper, and other Materials, of which the following is a specification.

10 My invention relates to improvements in machines for printing cloth, wall paper and other materials and has for its object to enable a printer to observe and distinguish objects printed on cloth, wall paper and other 15 materials while traveling through the printing machine.

Hitherto, in calico printing, a speed of about sixty yards a minute is considered the limit because of the difficulty, even at that 20 speed, of viewing and distinguishing the objects printed and detecting any faults of printing, such as imperfections of register. If, however the printer could observe the objects printed in such a way that he would be able to distinguish and detect any imperfections of register or faults of printing, a vastly increased speed and rate of printing could readily be attained and the object of 25 my invention is to enable the printer to so observe and distinguish the objects printed. I accomplish this object by the arrangement 30 use and application of a device such as a rotating disk having observation slits or apertures placed in front of the printing machine 35 at a suitable height and close to the cloth or other material as it leaves the engraved roller or other printing surface.

The disk is mounted on a carriage fitted on a traverse screw or otherwise suitably mounted 40 so as to be capable of being moved to and fro across the face of the cloth or other material and stopped at any desired point in its traverse. The disk is rotated by worm or other suitable gearing actuated preferably 45 from the driving shaft of the printing machine so that the rotations of the disk synchronize with the speed of travel of the material being printed.

In the accompanying sheet of drawings— 50 Figure 1 is a perspective view of a calico printing machine to which my invention has been applied. Fig. 2 is a front view of the stationary masking disk. Fig. 3 is a similar view of the rotating disk and Fig. 4 is a side

view of both disks and the worm gearing for 55 driving the rotating disk.

On the frame *a* of the machine I mount in bearings *b* a screw *c* which is driven in either direction as required by open and cross belts, not shown, and the well known arrangement 60 of two fast pulleys *d'*, *d''*, and a loose pulley *d*. On the screw *c* is mounted a carriage *e* which is traversed to the desired position to or fro along the face of the cloth *f* being printed whenever one of the driving belts is 65 on one of the fast pulleys *d'*, *d''*. A short shaft *g* is journaled in the carriage *e* and on this shaft is fixed the rotating disk *h* in which are formed any suitable number, say four, 70 observation apertures *h'*.

To prevent the eye becoming confused I prefer to mount on the traveling carriage *e* in front of the rotating disk *h* a masking disk *i* with only a single aperture *i'* which can be fitted with a magnifying lens to assist the 75 vision of the observer. This disk *i* is held against movement by the frictional engagement of its carrying parts but it may be rotated by hand when desired as it is sufficiently loose to permit such movement. 80

An electric or other light may be placed above the traveling carriage *e* with a reflector, if required, to focus the light on to the part of the printed material to be observed. On the shaft *g* of the rotating disk *h* is also fixed a 85 worm wheel *j* which gears with a worm *k* mounted in bearings *l* on the machine frame *a* and this worm *k* is driven by bevel gears *m* from a bevel gear *n* fixed on a shaft *o* carried in brackets *p* secured to the frame *a*. The 90 shaft *o* is driven by a sliding friction wheel *q* mounted thereon from a friction disk *r* fixed on the main shaft or other convenient rotating part.

To vary the speed of the shaft *o*, and consequently the speed at which the disk *h* is rotated, the friction wheel *q* is fitted to slide on a feather key in the shaft *o* and it is moved nearer to or farther from the center of the friction disk *r* by means of a guide bar *s* the 100 boss of which is mounted on a screw *t* journaled at its ends in the brackets *p* and actuated by a hand wheel *u*. The lower end of the bar *s* is guided by a rod *v* also supported in the brackets *p*. 105

In application the disk can be used in at least three ways for example:—

First. The disk *h* can be rotated so that a

single observation aperture h' therein will pass the eye of the observer say about three hundred times a minute; or to avoid rapid rotation of the disk h there may be two, three 5 or more observation slits or apertures h' therein, equidistant from each other, and in such case the rate of rotation of the disk may be reduced. As the objects which are printed 10 on the cloth are always exactly equidistant from each other, repeating at a specified distance, it follows that if the printed objects pass at a rate that is a multiple of three hundred times per minute, the objects will appear to be stationary, although in fact, only a 15 certain number are seen of those that pass.

Secondly. If, after having made the passage 20 of the observation apertures h' exactly synchronize with the passage of the printed objects as above described, the driving is adjusted by operating the hand wheel u so as to cause the disk h to rotate rather slower, the effect will be that the printed objects will appear to be gaining, that is, moving forward rather quicker than the disk.

Thirdly. If, after synchronizing, the motion 25 of the rotation of the disk h is slightly accelerated by again actuating the hand wheel u , the effect will be that the printed objects appear to be losing, that is, moving slowly back.

By utilizing the second and third modes the printer is able to examine the surface of the cloth or other material between the printed objects in order to detect printing faults.

30 What I claim and desire to secure by Letters Patent of the United States is:—

In a machine for printing cloth, wall paper or other materials—

1. The combination with a printing machine adapted to print on a traveling web, of 40 a disk rotatably supported from said machine in proximity to the path of said web and having a number of observation slits, substantially as described.

2. In combination, a traveling carriage 45 and means for traversing the same to and fro across the face of the material being printed, a rotating disk mounted on the traveling carriage and having any suitable number of observation apertures, a stationary masking disk with a single aperture mounted on the carriage in front of the rotating disk and means for varying the speed of the rotating disk, all substantially as and for the purposes herein set forth.

3. In combination, the traveling carriage e , the traverse screw c and means for rotating the same in either direction, the rotating disk h having any suitable number of observation apertures h' and the normally stationary 60 masking disk i with a single aperture i' said disk i being capable of rotary movement and means for rotating the disk h and varying its speed, all substantially as and for the purposes herein described.

In testimony whereof I have signed my name to this specification in the presence of two subscribing witnesses.

WILLIAM THOMAS HESKETH.
